US00D947933S

(12) **United States Design Patent** (10) Patent No.: **US D947,933 S**
(45) Date of Patent: **** Apr. 5, 2022**

(54) **PRINTER**

(71) Applicant: **Canon Kabushiki Kaisha**, Tokyo (JP)

(72) Inventor: **Takahiro Yamamoto**, Tokyo (JP)

(73) Assignee: **Canon Kabushiki Kaisha**, Tokyo (JP)

(**) Term: **15 Years**

(21) Appl. No.: **29/746,846**

(22) Filed: **Aug. 18, 2020**

(30) **Foreign Application Priority Data**

Feb. 18, 2020 (JP) ..... 2020-003051 D

(51) LOC (13) Cl. **14-02**
